Robert Magrane ATTORNEY

UNITED STATES PATENT OFFICE.

HARRY E. TOWNSEND, OF BROOKLYN, NEW YORK, ASSIGNOR TO ANCHOR CAP & CLOSURE CORPORATION, OF BROOKLYN, NEW YORK, A CORPORATION OF NEW YORK.

CLOSURE.

1,231,099.

Specification of Letters Patent. Patented June 26, 1917.

Application filed May 16, 1916. Serial No. 97,871.

To all whom it may concern:

Be it known that I, HARRY E. TOWNSEND, a citizen of the United States, residing at Brooklyn, in the county of Kings and State of New York, have invented new and useful Improvements in Closures, of which the following is a specification.

This invention relates to closures for receptacles and has particular reference to 10 metallic slip closures as applied to glass containers.

The objects of invention are to provide a closure that is cheap to manufacture, may be easily and quickly applied, that will not 15 easily be dislodged accidentally, and yet may be removed without difficulty when it is desired to open the package.

Referring to the drawings:

Figure 1 is a side elevation of the improved closure as applied to a glass container in the form of a tumbler;

Fig. 2 is a sectional elevation showing the closure ready to be forced upon the container;

Fig. 3 is a sectional elevation showing the form of the closure after it has been attached to "over-size" glass: and

Fig. 4 is a view similar to Fig. 3, showing the closure attached to "under-size" glass.

As shown in the figures, the closure comprises a body 10 from which depends an annular skirt. This skirt is preferably provided with two narrow vertical walls 11 and 12, and between these walls is located 35 an annular groove 13, the concave side of which is on the outer side of the skirt while the convex side is located on the inner side of the skirt and in contact with the glass 14.

In applying the cap, it is first placed in 40 the position shown in Fig. 2, and is then forced downward upon the glass, the skirt springing outward under the pressure and the convex side of the groove taking a frictional grip upon the glass, thereby producing 45 a sealing zone on the bead which is in very intimate contact with the glass side wall. The cap is easily applied in this manner as the wall 12 combined with the lower half of the groove 13 form a flaring 50 guide the opening of which is considerably larger than the outside diameter of the receptacle.

An important feature of this closure is 55 that it is adapted to seal differing sizes of receptacles. Glass receptacles, due to limi-

tations in their manufacture, vary greatly in size from standard dimensions. In the manufacture of a given size of glass, a great proportion of the receptacles run either under or over that size, sometimes 60 by several millimeters. In addition, a great deal of the glass is out of round or elliptical and in all of these cases it is difficult to provide a cap that seal such glass effectively. In my improved cap, these variations are 65 taken care of in large part by the annular groove 13, and as shown in Figs. 3 and 4, the spring of the skirt is such that the same sized cap will effectively close an over sized receptacle as shown in Fig. 3 or an 70 under sized receptacle as shown in Fig. 4.

When in place, the cap is attached to the glass with a tight frictional grip so that it may not be easily detached.

To remove the cap, the wall 11 is lightly 75 tapped with any object such as a knife or spoon. The tapping at this point has a peening effect, causing the groove 13 to flatten out and loosen its grip upon the receptacle. The closure may then be removed 80 with ease, and may be as easily replaced, though in the latter case, it will not fit as securely to the container as in the first instance.

I claim:

1. As an article of manufacture, a closure cap for containers of glass and the like, comprising a cover portion adapted to cover and protect the end of a suitable glass jar, a substantially uniform continuous skirt of 90 resilient material depending from the cover portion and at substantially right angles thereto, the skirt being provided with a continuous annular groove having the concave portion of the groove on the exterior 95 of the skirt and forming a continuous annular bead on the interior of the skirt, said groove being formed on such radius as to enable the bead to stretch and slightly flatten, thereby forming a sealing zone when the cap is forced over the substantially straight smooth side wall of a substantially incompressible container to permit the forces tending to restore the bead to normal shape 100 to cause the bead to form a tight friction seal with said side wall of the container.

2. A sealed package comprising a container of glass and the like, and having a substantially incompressible smooth cylindrical side wall, in combination with a seal 110

ing cap therefor comprising a cover portion adapted to cover and protect the end of the said container, a substantially uniform continuous skirt of resilient material depending from the cover portion and at substantially right angles thereto, said skirt being provided with a continuous annular groove having the concave portion thereof on the exterior of the skirt and forming a continuous annular bead on the interior of

the said skirt, said groove being formed on a relatively large radius to enable the bead to be stretched, whereby the bead exerts radial compression forces against the smooth side wall of the container over an 15 annular area comprising a sealing zone and forms a tight friction seal therewith, and enabling the cap to be removed without destruction.

HARRY E. TOWNSEND.
